UNITED STATES PATENT OFFICE.

ANDREW J. BOYNTON, OF MALDEN, MASSACHUSETTS.

TYPE-FORM FOR PRINTING PAPER-BAG TUBES.

SPECIFICATION forming part of Letters Patent No. 331,372, dated December 1, 1885.

Application filed March 18, 1884. Serial No. 124,608. (No model.)

To all whom it may concern:

Be it known that I, ANDREW J. BOYNTON, a citizen of the United States, residing at Malden, in the county of Middlesex and State of 5 Massachusetts, have invented a new and useful Improvement in Type-Forms for Printing Paper-Bag Tubes, of which the following is a specification.

The object of my invention is to so construct 10 and arrange the type-form on the cylinder of a tubing and printing mechanism that a tube may be printed when the paste between the folds is wet from the paster without destroying the adhesion of the folds of the tube to one 15 another. In this process of tubing the paper is necessarily folded so that one edge will overlap the other, and thus make along the center of the tube three thicknesses of paper, while there will be only two thicknesses at the sides. 20 Undue pressure upon the ridge thus formed forces the moisture from the paste into the body of the paper, entirely destroying its utility.

In the drawings, Figure 1 shows a bag-length printed on a form of the common construction, and Fig. 2 one printed on a form of my improved construction.

a represents the printed side of the tube, a' the folded side, and e the line of paste. 25 In the tube shown in Fig. 1, my experience shows that wherever the heavy letters—as the “o” in “Louis,” and the “o” in “Flour”—come upon the line of paste the pressure requisite to print the tube forces from the paste 30 its adhesive properties in all those places so pressed by the cut or types, thus making imperfectly-pasted bag-lengths, unsuitable for the uses for which they are designed until the holes

left in the seam have been patched by hand. To obviate this difficulty I have tried various 40 kinds of paste and glue; but the pressure necessary for printing destroyed the cohesive power of all materials with which I experimented where they were pressed by the type. I also removed portions of the blanket from 45 the line of paste, thus reducing the pressure upon it; but in this case it would receive no impression from the type. For these reasons I have contrived the construction and arrangement of the type upon the form to print upon 50 the bag, as shown in Fig. 2, and have removed all the heavy parts of the form from the line of the paste, so constructing the type that while bold, heavy printing is secured those portions of it which do come over the line of 55 paste are so slight—as the “o” in “Flour”—that their impact upon it will produce no injurious results.

By means of this construction and arrangement my bag-lengths are left thoroughly 60 pasted without injury from the printing process.

I claim as my invention—

In a mechanism for printing paper-bag tubes having a single wet paste-line, a type-form the body of which is adapted to make bold, heavy, printing on each side of said paste-line, the central part of the form being made with a very light face to make impression over the paste-line, substantially as and 65 70 for the purpose specified.

A. J. BOYNTON.
